CARBURETOR

Leo E. Oliver, Sanger, and Ray Carson, Sr.,
Vallejo, Calif.

Application November 21, 1944, Serial No. 564,450

16 Claims. (Cl. 48—180)

1

This invention is directed to, and it is an object to provide, a carburetor especially designed for use in a motor vehicle fuel system which includes a fuel reservoir containing a gaseous fuel, such as natural gas, under high pressure, a conduit leading from the reservoir to the carburetor, and a pressure regulator interposed in the conduit; such a fuel system being advantageous for automobiles, trucks, motor boats, and aircraft.

Another object of the invention is to provide a gaseous fuel carburetor which is constructed so as to effectively and economically meter the fuel, in correct proportions, at both low and high engine speeds; the carburetor including an effective idling feed to maintain the engine in operation when the throttle is closed.

An additional object of this invention is to provide a carburetor which requires no air choke mechanism for ease of starting.

A further object is to provide a carburetor for gaseous fuel, arranged so that exterior gas leaks cannot occur, as all working parts of the carburetor are subject to vacuum from the engine.

It is also an object to incorporate, in the carburetor, a low speed valve, and a high speed valve in unique combination; such valves being actuated in progressive order by a novel cam arrangement operated from the butterfly valve supporting throttle shaft of the device.

These objects are accomplished by means of such structure and relative arrangement of parts as will fully appear by a perusal of the following specification and claims.

In the drawings similar characters of reference indicate corresponding parts in the several views:

Figure 1 is a sectional elevation of the improved carburetor, with the low and high speed valves closed.

Figure 2 is a similar view, on reduced scale, but showing the low speed valve open.

Figure 3 is similar to Fig. 2, but shows both the low and high speed valves open.

Figure 4 is a diagrammatic view of the system in which the carburetor is embodied.

Referring now more particularly to the characters of reference on the drawings, the carburetor comprises a tubular body 1 open at one end to atmosphere and provided at the other end with an attachment flange 2 adapted to connect with the corresponding flange 3 of an engine manifold 4. A throttle shaft 5 extends diametrically through the body 1 intermediate its ends, and within said body the throttle shaft carries an air flow control butterfly valve 6, mounted as hereinafter described in detail, and which butterfly valve is

2

diagonally disposed when closed as shown in Fig. 1. The shaft 5 is fitted outside body 1 with a lever 7 to which a control rod 8 connects, said rod extending from the throttle pedal in the operator's compartment.

The body 1 forms the mixing chamber 9 of the carburetor, and a tubular, cylindrical housing 10 projects laterally from body 1 intermediate its ends; such housing being initially open at its outer end, and communicating at its inner end with chamber 9 directly above the low side of the butterfly valve 6 when the latter is closed.

A tubular sleeve 11 closely and symmetrically engages in housing 10, and adjacent its outer end this sleeve is threaded into the housing as at 12 for axial adjustment. The sleeve 11 is normally but releasably held in locked position by a nut 13 threaded thereon and abutting the adjacent end of housing 10.

The sleeve 11 carries the low and high speed valve assembly, which comprises the following:

A tubular plunger 14 is slidably disposed in sleeve 11 with its inner end intermediate the sleeve ends; said inner end of the plunger being

formed as an annular, radially projecting flange 15 riding in the sleeve. A closure plug 16 is threaded as at 17 into the housing at its outer end, and a helical compression spring 18 engages between said plug and the flange 15 normally

urging plunger 14 toward body 1. In the advanced position of the plunger, an annular, taper valve 19 thereon engages a cooperating seat 20 formed in the inner end of sleeve 11. This is the high speed valve of the carburetor, and adjacent

but short of said valve 19 there is space between the sleeve 11 and plunger 14 forming a gas flow chamber 21 which communicates with the interior of plunger 14 by means of a circumferential row of ports 21a in the latter. The inner end portion of plunger 14 projects beyond sleeve 11 to a termination in radial alignment adjacent but clear of the throttle shaft 5.

A mushroom head metering valve 22 cooperates with an annular taper valve seat 23 formed in

plunger 14 at the outer end thereof, and said valve 22 includes an actuating stem 24 which extends through said plunger in clearance relation except at the inner end thereof where a close running fit is provided; such clearance providing

a gas flow channel 25. A row of circumferentially spaced ports 26 open through the plunger 14 into channel 25 beyond the sleeve 11. The ports 21a likewise are in communication with channel 25. It should be noted that ports 21a are of greater diameter than ports 26.

A compression spring C seats between the head of valve 22 and the plug 16 normally holding said valve 22 closed; valve 22 being the slow speed valve of the carburetor.

The valve stem 24 terminates beyond the inner end of plunger 14 and is fitted with an enlarged head 27. A flat segmental cam 28 is fixed on throttle shaft 5 radially thereof, with the working edge of said cam eccentric to the shaft and riding the head 27 on valve stem 24; said cam extending across the shaft 5 on the side opposite the butterfly valve 6, and being disposed so that the low end of the cam engages head 27 when the butterfly valve is closed.

The butterfly valve is rotatably supported on the shaft 5 by a hanger H, and all motion of said butterfly valve is imparted thereto by the cam. However at opposite ends of the back edge thereof the cam initially has some clearance from the butterfly valve. When the throttle shaft 5 is in carburetor closing position, one end of the back edge of cam 28 engages an upstanding compression spring S on butterfly valve 6 and urges the latter to closed position. (See Fig. 1.) From this position the throttle valve can rotate to some extent in a clockwise direction without the other end of the back edge of the cam engaging the butterfly valve on the opposite side of the shaft 5. The advantage of this independent movement of the cam relative to the butterfly valve will hereinafter appear.

Gaseous fuel is supplied to the carburetor by a conduit 29 which leads from a tank 30 where the fuel, preferably natural gas, is held under pressure; there being a manually adjustable pressure regulator 31 interposed in conduit 29 and disposed in the operator's compartment. The conduit 29 is connected to the carburetor by a fitting 32 on and opening through the plug 16.

Fuel, under regulated pressure, feeds from conduit 29 into the chamber 33 formed in sleeve 11 between valve 22 and plug 16. When the throttle shaft 5 and the cam 28 are initially rotated in a clockwise direction from the closed position of Fig. 1, the cam moves independently of the butterfly valve and begins to depress head 27 and stem 24 causing an initial opening of valve 22. Gaseous fuel then first feeds into channel 25 and out of ports 26 into the mixing chamber 9. As this occurs before the butterfly valve 6 opens, the effect of an air choke is automatically obtained.

With continued clockwise rotation of the throttle shaft and cam, the valve 22 is fully opened, as shown in Fig. 2, with maximum low speed fuel delivery through ports 26.

Thereafter, with further clockwise rotation of said shaft and cam, the head 27 abuts against the adjacent end of plunger 14 and causes opening of high speed valve 19; fuel then passing from channel 25 through ports 21a into chamber 21 and thence about valve 19 into mixing chamber 9.

With opening of valves 22 and 19, as above described, except at the initial opening of valve 22, the cam engages and there is an accompanying progressive opening of butterfly valve 6 to provide access of air in proportion to fuel increase; fuel delivery being properly regulated to butterfly valve position by axial adjustment of sleeve 11 which carries the valve assembly.

The springs 18 and C return the valves to closed position in inverse progressive order to that above described, when the throttle shaft 5 is rotated counter-clockwise.

Idling fuel mixture is delivered to chamber 9, 75 slightly and to a predetermined extent independ-

when valves 19 and 22 are closed, by the following arrangement:

An air feed duct 34 leads through bdy 1 parallel to its axis and connects between atmosphere and the mixing chamber 9; there being a needle valve 35 to control air flow through said duct. Another cylindrical housing 36 projects from body 1 below housing 10, and is closed at its outer end while its inner end is in communication with a passage 37 leading to duct 34 inwardly of needle valve 35.

Fuel is fed into the housing 36 by a lateral conduit 38 leading from fitting 32 through the closed outer end of said housing. Fuel under pressure in housing 36 is fed into passage 37 and duct 34 in controlled quantity through the medium of a vacuum actuated, spring returned valve unit 39. The valve unit 39 includes an adjustment nut 40 which can be set to insure closing of the valve against fuel pressure tending to open the same, when the vacuum falls below idling pressure.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. A carburetor comprising a body forming a mixing chamber open at one end to atmosphere and adapted to feed a fuel mixture from the other end, a butterfly valve mounted for movement in said chamber intermediate the ends thereof, a fuel metering and delivery valve assembly mounted in connection with the body and in communication with the chamber between said other end thereof and the butterfly valve, the butterfly valve being supported by a throttle shaft, and a cam mounted on the throttle shaft operative to engage and progressively open said valve assembly upon rotation of said shaft to open the butterfly valve.

2. A carburetor comprising a body forming a mixing chamber open at one end to atmosphere and adapted to feed a fuel mixture from the other end, a butterfly valve mounted for movement in said chamber intermediate the ends thereof, a fuel metering and delivery valve assembly mounted in connection with the body and in communication with the chamber between said other end thereof and the butterfly valve, the butterfly valve being supported by a throttle shaft, and a cam mounted on the throttle shaft operative to engage and progressively open said valve assembly upon rotation of said shaft to open the butterfly valve.

3. A carburetor comprising a body forming a mixing chamber open at one end to atmosphere and adapted to feed a fuel mixture from the other end, a butterfly valve mounted for movement in said chamber intermediate the ends thereof, a fuel metering and delivery valve assembly mounted in connection with the body and in communication with the chamber between said other end thereof and the butterfly valve, the butterfly valve being supported by a throttle shaft, and a cam mounted on the throttle shaft operative to engage and progressively open said valve assembly upon rotation of said shaft to open the butterfly valve; said valve assembly being spring urged toward closed position.

4. A carburetor comprising a body forming a mixing chamber open at one end to atmosphere and adapted to feed a fuel mixture from the other end, a butterfly valve mounted for movement in said chamber intermediate the ends thereof, a fuel metering and delivery valve assembly mounted in connection with the body and in communication with the chamber between said other end thereof and the butterfly valve, and means operative to first open said valve assembly

70 thereof, a fuel metering and delivery valve assembly mounted in connection with the body and in communication with the chamber between said other end thereof and the butterfly valve, and means operative to first open said valve assembly

ently of the butterfly valve, and to then open said valve assembly and butterfly valve together and progressively.

4. A carburetor comprising a body forming a mixing chamber open at one end to atmosphere and adapted to feed a fuel mixture from the other end, a butterfly valve mounted for movement in said chamber intermediate the ends thereof, a fuel metering and delivery valve assembly mounted in connection with the body and in communication with the chamber between said other end thereof and the butterfly valve, and means operative to first open said valve assembly slightly and to a predetermined extent independently of the butterfly valve, and to then open said valve assembly and butterfly valve together and progressively; the butterfly valve being rotatably mounted on a throttle shaft extending into the mixing chamber, and said means including a cam fixed on said shaft, said cam upon rotation of the shaft in one direction being arranged to first engage and partially open the valve assembly and to then engage and open both the valve assembly and butterfly valve.

5. A carburetor comprising a body forming a mixing chamber open at one end to atmosphere and adapted to feed a fuel mixture from the other end, a butterfly valve mounted for movement in said chamber intermediate the ends thereof, a fuel metering and delivery valve assembly mounted in connection with the body and in communication with the chamber between said other end thereof and the butterfly valve, said valve assembly including a low speed valve and a high speed valve, and means to open the butterfly valve and said valve assembly together and progressively; the low speed valve opening first followed by the opening of the high speed valve.

6. A carburetor as in claim 5 in which said valve assembly includes a stem depressible to open the low speed valve, and a plunger depressible to open the high speed valve; said means being operative to depress the stem, and the stem after predetermined depression thereof, engaging and depressing the plunger.

7. A carburetor comprising a body forming a mixture chamber open at one end to atmosphere and adapted to feed a fuel mixture from the other end, a butterfly valve mounted for movement in said chamber intermediate the ends thereof, a cylindrical housing projecting laterally from the body, the housing being closed at its outer end and in communication at its inner end with the mixing chamber between said other end thereof and the butterfly valve, a fuel feed conduit connected into the housing adjacent its outer end, a fuel metering and delivery valve assembly slidably mounted in the housing and closing toward the mixing chamber, spring means normally urging the valve assembly to closed position, and means to open the butterfly valve and said valve assembly together and progressively.

8. A carburetor comprising a body forming a mixing chamber open at one end to atmosphere and adapted to feed a fuel mixture from the other end, a butterfly valve mounted for movement in said chamber intermediate the ends thereof, a cylindrical housing projecting laterally from the body, the housing being closed at its outer end and in communication at its inner end with the mixing chamber between said other end thereof and the butterfly valve, a fuel feed conduit connected into the housing adjacent its outer end, a tubular plunger slidable in the housing, an annular valve between the housing and plunger

closed upon movement of the plunger toward the mixing chamber, spring means normally urging the plunger to valve closing position, said plunger having ports therethrough on opposite sides of said annular valve, another valve arranged to close the end of the plunger opposite the mixing chamber, said other valve including a valve stem extending through the plunger and terminating beyond the inner end of the latter, there being a fuel flow clearance in the plunger from said other valve to said ports, other spring means normally urging said other valve to closed position, and means operative to first engage and move said stem to open said other valve, and to then engage and move the plunger to open said annular valve.

9. A carburetor as in claim 8 in which said spring means cooperating with the plunger, and other spring means cooperating with said other valve, comprise compression springs, one within the other, engaged between the closed outer end of the housing and adjacent portions of the plunger and other valve.

10. A carburetor comprising a body forming a mixing chamber open at one end to atmosphere and adapted to feed a fuel mixture from the other end, a butterfly valve mounted for movement in said chamber intermediate the ends thereof, a cylindrical housing projecting laterally from the body, the housing being closed at its outer end and in communication at its inner end with the mixing chamber between said other end thereof and the butterfly valve, a fuel feed conduit connected into the housing adjacent its outer end, a tubular plunger slidable in the housing, an annular valve between the housing and plunger closed upon movement of the plunger toward the mixing chamber, spring means normally urging the plunger to valve closing position, the butterfly valve being mounted on a transverse throttle shaft in the body, and a cam mounted on said shaft, said cam being arranged to function upon rotation of the shaft to first cause movement of the stem and opening of said other valve, and then cause movement of the plunger and opening of said annular valve.

11. A carburetor as in claim 10 in which both the plunger and stem project into the mixing chamber to adjacent but short of the throttle shaft, the stem projecting slightly further than the plunger, and a head on the stem beyond the plunger; the cam riding said head, and the head engaging the plunger after predetermined movement thereof by the cam.

12. A carburetor as in claim 10 in which the butterfly valve is rotatable on the throttle shaft; said cam being operative to first cause movement of the stem and partial opening of said other valve independent of the butterfly valve, and to then engage the butterfly valve and thereafter cause opening thereof progressively with continued opening of said other valve and subsequent opening of said annular valve.

13. A carburetor comprising a body forming a mixing chamber open at one end to atmosphere and adapted to feed a fuel mixture from the other end, a butterfly valve normally closing the passageway through the body, a normally closed gas valve connected with the body between said other end thereof and the butterfly valve, such gas valve including a valve stem projecting into the body, a cam mounted for rotation within the body, such cam being engageable with said stem to operate said gas valve and said cam being also engageable with the butterfly valve to move it

from closed to open position, and means to feed fuel to the gas valve.

14. A carburetor as in claim 13 in which the movement of the cam first engages and moves the stem to partially open the gas valve, and thereafter the cam engages and opens the butterfly valve while continuing to move the stem to further open the gas valve.

15. A carburetor comprising a body forming a mixture chamber open at one end to atmosphere and adapted to discharge a fuel mixture from the other end to an engine, a butterfly valve normally closing the passage through the body, a source of fuel supply, two fuel feed passages leading from the fuel supply source to said other end of the chamber and to the same side of the butterfly valve, a valve in each passage, one passage constituting a fuel feed for the engine when idling, and the other constituting a main fuel feed to the engine, and means operable to partially open the valve in the main fuel feed passage without opening the butterfly valve whereby fuel may flow from the main fuel supply to the engine without atmospheric air being mixed therewith.

16. A carburetor as in claim 15, including means to progressively move the last named valve from said partially opened position to full open position synchronously with the opening of the butterfly valve.
